UNITED STATES PATENT OFFICE.

GEORGE L. HARVEY, OF CHICAGO, ILLINOIS.

DRAW-GEAR FOR RAILWAY-CARS.

SPECIFICATION forming part of Letters Patent No. 447,824, dated March 3, 1891.

Application filed September 20, 1890. Serial No. 365,621. (No model.)

To all whom it may concern:

Be it known that I, GEORGE L. HARVEY, a citizen of the United States, residing at Chicago, Illinois, have invented certain new and useful Improvements in Draw-Gear, of which the following is a specification.

My invention relates to a novel construction of draw-gear for railway-cars. The usual draw-gear comprises metal stop-blocks which are secured upon wooden sub-draft-sills, the latter being bolted to the main floor-sills. As is well-known, standard heights for the floor and for the draw-gear have been adopted by the car-builders of this country, to which most cars are conformed. To meet the requirements of these standards these supplemental draft-sills have been employed. The weight of a set of these timbers, metal stop-blocks, and bolts is considerable. Besides the objection on account of weight is that of cost and lack of security, as draw-gears of this construction are difficult to sustain in position under the shocks and strains of service, and are frequently stripped from the sills. I have devised a draw-gear which obviates these objections, which is strong, light, and efficient in service, and which is readily conformed to the standards.

My invention consists in a draw-gear whose draft members are bent metal plates adapted to be secured directly to the sides of the main sills and of such depth as to project below said sills, and which are provided in the projecting portions with offsets which receive the follower-blocks. These plates are thus made to take the place of the draft-timbers and stop-blocks of the usual draw-gear; but they are adapted to the standard spring-pocket and draw-head. These draft-plates are made from metal in any convenient manner, as by bending, forging, or rolling, but are preferably made from steel plates cut to shape and pressed to form. These plates are secured by their upper margins upon the sides of the main sills by bolts or rivets, and they preferably have a bearing at their forward ends against the rear sides of the end sill.

In the accompanying drawings, Figure 1 is a side elevation of the draw-gear and draw-head. Fig. 2 is a plan view; Fig. 3, a perspective of one of the plates; and Fig. 4 is an elevation and section on line 4-4 of Fig. 2.

In the construction illustrated in the drawings double sills are employed for the floor-frames, said sills being metal channel-beams. 55 Wooden sills may be employed. The members of the double longitudinal sills are marked A A' and the members of the end sill B B'.

C represent the draft-plates. Their form 60 is best shown in Fig. 3, and said plates are duplicates of each other. Each may have the marginal strengthening-flange c, which also serves for a bolt-flange to abut against the end sill and to sustain the straps D for the 65 follower-blocks.

Each of the plates C has the integrally-formed offset portion C', and when said plates are secured with the openings of the offset portions opposite, a pocket is provided thereby 70 to receive the follower-blocks and spring E, to which the usual draw-head F will be attached.

Plates C are apertured along their upper edges, and bolts or rivets G secure them to 75 the sill members. The plates are preferably so placed as to abut at their forward ends against the end sills, and bolts are passed through their flanges c to anchor the plates to the end sills. 80

By reference to the drawings, Figs. 1 and 4, it will be observed that the offset portions forming the pocket are formed in the parts of the plates which project below the plane of the bottom of the sills. This construction has 85 many advantages. It gives a broad plate upon which the strain is exerted edgewise. It enables the supplemental draft-sills and their fastening-bolts and stop-blocks to be dispensed with and permits a direct connection 90 with the main sills and the location of the draft-bar in conformity to the standard. The structure is capable of sustaining much greater shock than the draw-gears in general use, and is much lighter. 95

My invention is particularly applicable to metal cars which have not heretofore been provided with a practical draw-gear. Of course the specific form and configuration of parts are not essential, and I do not therefore limit 100 my invention to these details.

In a pending application, Serial No. 357,179, filed August 14, 1890, I have shown and described one form of my invention, and I do

not herein intend to claim the particular construction described and claimed in said application.

I claim—

- 5 In a draw-gear, a draft-connection comprising two metal plates having integral extensions adapting them to be secured to the sides of the longitudinal sill or sills of a car, and

integral portions projecting below the sills and having therein offsets to provide bearings for the draw-head connections, substantially as set forth.

GEORGE L. HARVEY.

Witnesses:

FREDERICK C. GOODWIN,
C. C. LINTHICUM.
